UNITED STATES PATENT OFFICE.

JAMES W. BOWERS, OF PEARLINGTON, MISSISSIPPI.

ENVELOPE OPENER.

Application filed December 7, 1925. Serial No. 73,737.

This invention relates to an envelope opener, one of the objects being to provide a device of this character utilizing a cutting blade for insertion beneath the flap of an envelope after which, by thrusting with the opener, the paper may be cut along the fold of the flap.

A further object is to provide a tool of this type the blade of which can be shifted so as to be completely housed within the body portion of the tool when not used, thus allowing the tool to be carried conveniently in the pocket.

Another object is to provide simple means whereby the blade can be secured in either active or inactive position.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings, the preferred form of the invention has been shown.

In said drawings,

30 Figure 1 is a side elevation of the device. Figure 2 is a section on line 2-2 Figure 1.

Figure 3 is a section on line 3-3 Figure 1.

Referring to the figures by characters of reference 1 designates a longitudinally channeled body preferably formed of sheet metal and provided at one end with a cylindrical tubular handle 2.

Formed in one side of the body 1 is a longitudinal slot 3 while in the opposite side of the body are spaced apertures 4 and 5. A spring strip 6 is slidably mounted on the slotted side of the body and has one end portion slidable within a slot 7 formed in the handle 2 adjacent the point where it merges into the body 1. One end of this spring strip 6 is adapted to bear slidably upon the inner surface of the handle 2 as shown at 8 while the other end portion of the strip is bent outwardly to constitute a finger piece 9. A stud 10 is carried by the spring strip 6 close to the finger piece 9 and extends through the slot 3. This stud is adapted to be seated within either one of the apertures 4 and 5.

A detachable cutting blade has been indicated at 11. This blade has a straight cutting edge 12 and a curved back edge 13. The

inner or butt end of the blade is provided with a reinforcing head 14 adapted to fit snugly within the channeled body as shown in Figure 2. An opening 15 is formed in the 60 blade and is designed to receive the stud 10.

When it is desired to use the blade 11 for the purpose of opening an envelope or the like, the finger piece 9 is pulled outwardly a sufficient distance to withdraw the stud 10 65 from the opening 5 but not to withdraw it from the opening in the blade 11. Said finger piece is then thrust forwardly so that the end portion 8 of the strip 6 will slide along the inner surface of the handle 2. This movement is continued until the stud 10 comes opposite the opening 4 at which time it will swing into said opening and thus lock the blade 11 projected beyond the body 1 as shown in Figure 1. Thereafter the blade 70 can be retracted into the body 1 simply by again pulling outwardly on the finger piece 9. This will disengage the stud 10 from the wall of the opening 4. The strip 6 can then be slid backwardly to the position shown in 75 Figure 2 whereupon the stud 10 will snap into the aperture 5 and fasten the blade 11 in retracted position.

When it is desired to remove the blade bodily from the channeled portion 1 the finger 80 piece 9 is pulled outwardly a sufficient distance to withdraw the stud 10 from the opening 15 in the blade. Said blade can then be taken out of the body, sharpened, and replaced, or a new blade can be inserted. As the curved 90 back of the blade constantly projects out of the channel, it can be grasped at any time whether the blade is projected or retracted, when it is desired to remove the blade. Thus 95 the removal can be effected with perfect safety as the cutting edge 12 will not be presented.

What is claimed is:

A tool of the class described including a tubular handle, a longitudinally channeled body extending from one end thereof, said body cooperating with one side of the handle to form an obtuse angle, there being a slot in the angle portion opening into the handle, a blade normally housed in the channeled body having a longitudinal cutting edge supported in the inner portion of the channeled body and a longitudinally bowed back edge normally projecting outwardly from the channeled body, there being a longitudinal slot in one side of the body, a spring strip extending through the slot in the angle 100 105 110

portion and projecting into and slidable within the handle, one end of the strip bearing against the handle at one side of the inner surface thereof and the other end bearing against the outer surface of one side of the body, there being an outwardly extended portion on the strip constituting a finger piece, and a pin extending from this strip through the slot in the body and detachably engaging the blade, said strip and

pin constituting means for sliding the blade longitudinally of the body to project one end thereof beyond the body, there being openings in one side of the body for the reception of the pin to hold the blade in either of two extreme positions. 15

In testimony that I claim the foregoing as my own, I have hereto affixed my signature.

JAMES W. BOWERS.
